UNITED STATES PATENT OFFICE.

MORITZ LEVI, OF NEW YORK, N. Y., ASSIGNOR OF ONE-HALF TO RASMUS FORSHOLM, OF SAME PLACE.

ELECTRIC ADVERTISING-CLOCK.

SPECIFICATION forming part of Letters Patent No. 437,905, dated October 7, 1890.

Application filed June 26, 1890. Serial No. 356,756. (No model.)

To all whom it may concern:

Be it known that I, MORITZ LEVI, of the city, county, and State of New York, a citizen of the German Empire, have invented certain 5 new and useful Improvements in Electric Advertising-Clocks, of which the following is a specification.

This invention relates to an improved advertising-clock of that class in which a number 10 of sheets containing announcements are applied to an intermittently-rotating drum or cylinder and successively exhibited in a front opening of the clock-case by the action of electrical agencies.

15 The invention consists of a clock-movement that is provided with a circuit-closing device by which the armature of an electro-magnet is intermittently actuated, so that it transmits by a pawl-and-ratchet device intermittent rotary motion to a drum to which a number of 20 sheets that contain announcements are applied, said announcements being successively exhibited through an opening in the front wall of the clock-case, as will be fully described 25 hereinafter, and finally pointed out in the claims.

In the accompanying drawings, Figure 1 represents a front elevation of my improved electric advertising-clock. Fig. 2 is a sectional 30 front elevation of the interior construction of the same, the front wall of the clock-casing being removed, so as to show the interior parts. Fig. 3 is a vertical transverse section on the line 2 2, Fig. 2; and Fig. 4 is a vertical 35 transverse section of the drum to which the advertising-sheets are applied.

Similar letters of reference indicate corresponding parts.

Referring to the drawings, A represents a 40 clock-movement, and B the casing of the same. In the front wall of the casing B is arranged an oblong or other opening b, in which a number of announcements are printed on suitable sheets, which are successively exhibited. 45 The clock-movement A is arranged at the upper part of the case and provided with a circuit-closing device C, which is composed of a rotating arm d on one of the arbors of the clock-train, and a contact-spring d', that is attached to an insulated block d² of the casing 50

B, said arm and spring being in circuit with a battery that is preferably arranged in the lower part of the clock-casing. The rotary arm d is provided with a platinum contact-pin that forms at each rotation of the arm contact 55 with the spring d', so as to close and interrupt thereby at regular intervals of time the circuit of the battery. The circuit-closing arm d is electrically connected with the frame of the clock-train and with an electro-magnet E, 60 that is located in the battery-circuit, said electro-magnet operating an armature-lever E', which is fulcrumed to a bracket-arm e at the interior of the casing B. The upper end of the armature-lever is connected by a spiral 65 spring e' with the casing B, while the lower end of the armature-lever engages by a pivoted and spring-actuated pawl f a ratchet-wheel f' on the shaft of a drum or cylinder F, which cylinder turns in bracket-shaped bearings f², applied to the clock-casing. A check-pawl f³ engages the ratchet-wheel f' and prevents it from being turned in the opposite direction. A stop f⁴ retains the lower end of 70 the armature-lever E' when the same is not 75 attracted by the electro-magnet E.

To the circumference of the drum F is applied a number of advertising-sheets g by means of thin wires that are inserted into longitudinal grooves arranged equidistantly 80 on the surface of the drum, said sheets containing the announcements that are to be exhibited in the front opening of the clock-casing B. The outer ends of the sheets g are held on the drum F by means of a suitable 85 spring or other retaining device g', that is applied to the rear wall of the clock-casing below the clock-movement A, said spring pressing on the sheets, so as to permit them to drop successively as one sheet after the other 90 passes below the retaining-spring, as shown in Fig. 4.

My improved advertising-clock operates as follows: At each rotation of the arm d of the clock-train it forms contact with the spring 95 d, and closes thereby the circuit of the battery, the current energizing the cores of the electro-magnet, so that the fulcrumed armature-lever E' is attracted. The pawl f on the armature-lever engages thereby the ratchet- 100

wheel f' on the shaft of the drum and causes the turning of the latter for the distance of a tooth. By the intermittent rotary motion that is imparted by the armature and the 5 pawl-and-ratchet mechanism to the drum the sheets containing the announcements are successively dropped and exhibited in the front opening of the clock-casing. The dial of the clock is arranged at the front wall of the clock 10 above the opening b , the hands being operated by the clock-train in the usual manner, which serves also to operate the circuit-closing device, so that the armature-lever and pawl-and-ratchet mechanism are operated and an 15 intermittent rotary motion imparted to the drum, by which the sheets containing the announcements are successively dropped and exhibited.

Having thus described my invention, I 20 claim as new, and desire to secure by Letters Patent—

1. The combination of a clock-movement, a clock-casing having a front opening, a circuit-closing device operated intermittently by 25 said clock-movement, an electro-magnet arranged in circuit with the circuit-closing device, an armature-lever operated by said

electro-magnet, a drum having a number of sheets containing announcements, and a pawl-and-ratchet mechanism by which the armature-lever imparts intermittently-rotating motion to the drum so as to exhibit said sheets through the front opening of the clock-casing, substantially as set forth. 30

2. The combination of a clock-movement, 35 a circuit-closing device operated by said clock-movement, an electro-magnet arranged in circuit with said circuit-closing device, an armature-lever operated by said magnet, a drum having a number of sheets containing announcements attached to the circumference of the drum, a pawl-and-ratchet device for intermittently rotating the drum, and a retaining device for holding said sheets on the circumference of the drum and successively dropping 40 them for exhibition, substantially as set forth. 45

In testimony that I claim the foregoing as my invention I have signed my name in presence of two subscribing witnesses.

MORITZ LEVI.
